UNITED STATES PATENT OFFICE.

ORVILLE M. MORSE, OF JACKSON, MICHIGAN.

AUTOMATIC GRAIN-SCALES.

SPECIFICATION forming part of Letters Patent No. 431,703, dated July 8, 1890.

Application filed July 2, 1889. Serial No. 316,282. (No model.)

To all whom it may concern:

Be it known that I, ORVILLE M. MORSE, a citizen of the United States, residing at Jackson, in the county of Jackson and State of Michigan, have invented new and useful Improvements in Automatic Scales, of which the following is a specification.

This invention relates to that class of automatic scales which are used for weighing grain and similar substances or material, and which are provided with a rotative wheel containing buckets and mounted in a scale-beam underneath the supply-hopper, so that the material flows from the hopper into the bucket underneath the hopper until the weight of the material delivered into the bucket preponderates, when the bucket-wheel descends, and thereby releases itself and makes a partial revolution sufficient to discharge the material from the filled bucket and bring the next succeeding empty bucket underneath the hopper.

The principal object of my invention is to improve the devices whereby the rotative bucket-wheel is locked and released, so that the wheel is positively locked against further rotation at the end of every partial revolution, thereby preventing the wheel from making more than one partial revolution upon the filling and discharging of one bucket.

My invention has the further object to improve the scale in other respects, as will be hereinafter fully set forth, and pointed out in the claims.

In the accompanying drawings, Figure 1 is a vertical section of an automatic scale provided with my improvements. Fig. 2 is a horizontal section thereof. Fig. 3 is a fragmentary vertical section showing the locking-bolt released.

Like letters of reference refer to like parts in the several figures.

A represents the stationary frame of the scale; B, the scale-beam mounted on said frame in any suitable manner and provided with a weight b; C, the bucket-wheel pivoted in the arms of the inner open or loop-shaped portion of the scale-beam, and D the feed-hopper arranged above the bucket-wheel.

d is a valve which is hung at the mouth of the feed-hopper and provided with a laterally-extending arm e, the weight of which

tends to hold the valve closed. The bucket-wheel is provided with radial partitions f, which are secured to the heads F F of the wheel and divide the wheel into buckets g.

H is a locking-bolt, by which the wheel is locked in position against further rotation at the end of every partial revolution, and which is capable of vertical movement in a guide h, secured to the side of the feed-hopper.

I is a locking-pawl, which engages in a notch or groove i in the bolt H, and holds the latter in an elevated position. This locking-pawl is pivoted to a lug j on the feed-hopper 65 above the locking-bolt and is provided with an actuating-arm J, which extends downwardly over the bucket-wheel.

L represents a series of cams secured to the bucket-wheel equal in number to the number 70 of buckets and each terminating at its raised end in a projecting stop l, which is adapted to engage against the locking-bolt H.

K represents a detent-pawl, by which the bucket-wheel is prevented from turning backward. This pawl is attached to the front portion of the scale-beam adjacent to the bucket-wheel and adapted to engage with the stops l thereof; but it may be constructed and arranged in any other suitable manner. 80

In the position of the parts represented in Fig. 1 the wheel is locked in position by one of the stops l acting against the locking-bolt H. The valve d at the mouth of the hopper is held open by its arm e being raised by the 85 rear partition f of the bucket which is receiving the grain. The locking-bolt H is in its elevated position, in which it is held by the locking-pawl I, engaging in the groove i of the bolt. The locking-pawl is held in engagement with said groove by the weight of the depending actuating-arm J, which clears the adjacent stop l of the wheel in this position. When the upper bucket has received the

quantity of grain which balances and slightly 95 overcomes the weight on the scale-beam, the bucket-wheel descends with the inner portion of the scale-beam, thereby causing the valve-arm e to descend also and the valve to close. The downward movement of the 100 bucket-wheel continues until the stop l resting against the locking-bolt clears the latter, when the bucket-wheel turns in the direction of the arrow in Fig. 1, causing the discharge

of the material from the loaded bucket. When the bucket-wheel begins to turn, the stop *l*, adjacent to the actuating-arm *J* of the locking-pawl *I*, swings this arm outward and withdraws the pawl from the notch of the locking-bolt, allowing the latter to descend upon the depressed portion of the cam *L* in rear of the stop *l*, as represented in Fig. 3. The descent of the bolt may be accelerated by a spring *m*. The bucket-wheel continues its rotative movement with the bolt resting on the cam, which latter gradually elevates the bolt until its groove coincides with the end of the locking-pawl, when the pawl enters the groove and again locks the pawl in its elevated position.

The locking-bolt bearing upon the cam during the rotative movement of the bucket-wheel retards the motion of the wheel and prevents undue speed. This pressure upon the cam is increased by the spring bearing upon the locking-bolt. The pressure of the locking-pawl against the locking-bolt also retards the movement of the wheel.

The locking-bolt is dropped below its locking-position when released and then again raised to its locking position, which latter is reached just before the stop comes in contact with the bolt, whereby the bolt is brought in contact with the wheel long before the stop strikes the bolt, thereby preventing the stop from passing by the bolt and the scale from missing a bucket.

I claim as my invention—

1. The combination, with the scale-beam and the rotative bucket-wheel provided with stops and cams in front of said stops, of a movable locking-bolt against which said stops engage and which is elevated to its locking position by said cams, substantially as set forth.

2. The combination, with the scale-beam and the rotative bucket-wheel provided with stops, of a locking-bolt and a locking-pawl by which the bolt is held and released, substantially as set forth.

3. The combination, with the scale-beam and the rotative bucket-wheel provided with stops, of a locking-bolt and a locking-pawl provided with an actuating-arm, substantially as set forth.

4. The combination, with the scale-beam and the rotative wheel mounted on the same and provided with stops, of a locking-bolt against which said stops engage and which is capable of downward movement in the direction in which the wheel is depressed by the load, cams whereby the bolt is elevated after it has passed below its normal position, and a pawl whereby the bolt is held in its normal position, substantially as set forth.

Witness my hand this 25th day of June, 1889.

ORVILLE M. MORSE.
